UNITED STATES PATENT OFFICE.

EDWARD FOURNIER, OF PLATTSBURG, NEW YORK.

NON-REFILLABLE BOTTLE.

1,077,825.

Specification of Letters Patent.

Patented Nov. 4, 1913.

Application filed September 6, 1912. Serial No. 718,962.

To all whom it may concern:

Be it known that I, EDWARD FOURNIER, a citizen of the United States, residing at Plattsburg, in the county of Clinton and 5 State of New York, have invented new and useful Improvements in Non-Refillable Bottles, of which the following is a specification.

An object of the invention is to provide 10 a bottle that cannot be conveniently refilled after the original contents thereof has been withdrawn therefrom.

The invention embodies, among other features, a casing for insertion in the neck of a 15 bottle body, the said casing being of a tubular nature and having a weighted valve movable therein to normally close a passage in the casing and prevent persons from forcing or otherwise pouring a fluid into the 20 bottle body after the original contents thereof has been withdrawn therefrom.

In the further disclosure of the invention reference is to be had to the accompanying 25 drawings, constituting a part of this specification, in which similar characters of reference denote corresponding parts in all the views, and in which:

Figure 1 is a fragmentary vertical sectional view of the bottle, the valve being 30 shown in closed position; Fig. 2 is a similar vertical sectional view showing the bottle body tilted with the valve in open position; Fig. 3 is a horizontal sectional view taken on the line 3—3 in Fig. 1; Fig. 4 is a perspective view of the valve; and Fig. 5 is a perspective view of the valve supporting member, looking toward the under side thereof.

Referring more particularly to the views, 40 use is made of a bottle body 10 terminating in a neck 11 in which is mounted a tubular casing 12, preferably made of cork, the said casing having an annular groove 13 in which is mounted a split spring-like locking rod 14 which, when the casing 12 is placed within the neck 11 so that the groove 13 registers with a groove 15 formed in the neck 11 of the bottle body, will spring into the groove 15, thus locking the casing 12 45 within the neck 11 of the bottle body 10.

The casing 10 is provided with a tubular head 16 having an annular member 17 reposing upon the upper edge of the bottle body 10 and the head 16 is provided with a 50 restricted passage 18 terminating in a valve chamber 19 within the casing 12, a baffle

plate 20, provided with supporting lugs 21, being arranged within the valve chamber 19 with the supporting lugs connected to the walls of the valve chamber to rigidly secure 60 the baffle plate within the same, it being readily seen that when the bottle body is tilted the liquid will flow outwardly between the supporting lugs 21 of the baffle plate and the peripheral edge of the baffle plate 65 and the circular wall of the valve chamber 19.

A valve supporting member 22 is mounted within the lower end of the casing 12 and is provided with a passage 23, a valve seat 24 being formed on the upper edge of the valve supporting member 22 and a guide member 25 being formed with the valve supporting member 22 and depending therefrom to receive through an opening 26 therein, a silk cord 27 having a ball weight 28 secured to the lower end thereof. A valve 29 is mounted to slide within the valve chamber 19 and normally reposes upon the valve seat 24, the upper end of the cord 27 being secured to the under side of the valve 29 so that the weight of the ball 28 will hold the valve 29 on the valve seat 24 when the bottle body is in upright position, the mentioned valve 29 being provided with a 70 series of guide lugs 30 for preventing the valve 29 from tilting within the valve chamber 19, the said valve 29 being also provided with a series of cut away portions 31 through which the liquid from the interior 75 of the bottle body 10 is adapted to flow when the valve is unseated from the valve seat 24.

In the use of the device described, when the bottle body 10 is in upright position as 80 shown in Fig. 1, the weight of the ball 28 will hold the valve 29 on the valve seat, thus closing the passage 23 in the valve supporting member 22 and preventing anyone from forcing a liquid through the neck of the bottle body 10 and into the interior of the bottle body, it being readily apparent that tools or wires will also be prevented from being inserted in the neck of the bottle body by 85 providing the baffle plate 20, mounted on the upper end of the valve chamber 19 and thence to the restricted passage 18. Now when the bottle body is tilted, the fluid pressing against the under side of the valve 29 will unseat the valve, sliding the same 90 forwardly in the chamber 19, so that the fluid passing through the passage 23 will 95

110

pass through the cut away portions 31 of the valve 29 and thence through the valve chamber 19 and the passage 18, the mentioned fluid being adapted to pass between 5 the supporting lugs 21 and the periphery of the baffle plate 20 in the wall of the valve chamber 19 as mentioned heretofore. At the moment the bottle body 10 is replaced in an upright position, the liquid pressure 10 against the valve will be discontinued and the weight of the ball 28 together with the weight of the valve 29 will cause the valve to gravitate into closed position and repose upon the seat 24.

15 Having thus described my invention, I claim:

In a non-refillable bottle, the combination with a bottle body, of a tubular casing depending within the neck thereof, a valve 20 supporting member rigidly carried in the said casing and provided with a passage, a valve mounted to slide in the casing and normally seating on the valve supporting member to close the said passage, a guide mem-

ber formed integrally with the valve supporting member and connected thereto by a shank projecting from an edge of the valve supporting member to support the guide member in parallel relation to the under face of the valve supporting member, with a passage in the guide member in vertical alignment with the passage in the valve supporting member, a cord secured to the said valve and passing through the passage of the valve supporting member and the passage of the guide member, and a ball weight secured to the lower end of the said cord and arranged beneath the said guide member, the movement of the said valve in the said valve casing being limited by the said ball weight engaging the said guide member.

30 35 40 In testimony wherof I affix my signature in presence of two witnesses.

EDWARD FOURNIER.
